DEVICE FOR INDICATING THE RISE OF MOLTEN METAL TO A PREDETERMINED LEVEL IN A MOLD

Thomas H. Ivory, 16 S. 4th St., Duquesne, Pa.
Filed Jan. 2, 1959, Ser. No. 784,628
3 Claims. (Cl. 22—139)

This invention relates to a device for indicating the rise of molten metal to a predetermined level as it is teemed into a mold.

The device is particularly useful in combination with a mold in which steel ingots are cast and which is equipped with a hot top. A conventional hot top includes a refractory lined open ended metal casting supported on blocks which rest on the upper surface of an ingot mold. Its purpose is to maintain a reservoir of molten steel for feeding back into voids which form as an ingot solidifies. The lower portion of a hot top projects downwardly within the upper portion of the mold cavity. When molten steel is teemed into the mold, its flow should be stopped momentarily as the level reaches the lower end of the hot top. This pause enables some steel to solidify below the hot top casting and thus prevents steel from rising into the space between the casting and mold. Otherwise steel can solidify in this space and cause hot top "stickers." When "stickers" occur, valuable time is lost in stripping hot tops, and their refractory linings may be damaged or their castings cracked. Nevertheless the invention is not limited to this application, but may be used elsewhere for overcoming similar problems.

An object of the present invention is to provide, in combination with a mold, a device which furnishes a conspicuous visible indication when metal reaches a predetermined level in the mold.

A further object is to provide, in combination with an ingot mold and a hot top, a device which furnishes an indication when metal teemed into the mold reaches the bottom of the hot top, thus enabling the operator to cease pouring until the necessary solidification takes place to prevent metal from rising into the space between the hot top casting and mold.

A more specific object is to provide, in combination with an ingot mold and a hot top, an indicating device which includes a strip of magnesium or equivalent fixed to the lower portion of the hot top to be ignited when molten metal reaches its level and thus furnishing a conspicuous indication.

In accomplishing these and other objects of the invention, I have provided improved details of structure, a preferred form of which is shown in the accompanying drawing, in which:

The single FIGURE is a side elevational view, with parts broken away, showing a portion of an ingot mold and hot top equipped with an indicating device in accordance with my invention.

The figure shows the upper portion of a conventional big-end-up ingot mold 10 which has a cavity 12. A hot top 13 is supported on wood blocks 14, which rest on the upper surface of the mold in the conventional way. The lower portion of the hot top extends downwardly within the mold cavity 12. A sand ring 15 underlies the bottom surface of the hot top and is held in place by wire clips 16, which are received in openings in the hot top casting and extend under the ring in the conventional way.

2

In accordance with my invention, I mount a strip 17 of magnesium or equivalent substance capable of producing a conspicuous flare outside the hot top adjacent its lower edge. The strip is located out of the direct path of molten steel teemed into the mold to prevent its igniting prematurely. Conveniently the strip can be mounted between the outer surface of the sand ring 15 and the wire clips 16, although other equivalent mounting means can be used. When molten steel is teemed into the mold and reaches the level of the strip, the heat ignites the strip, which furnishes a conspicuous signal. Thus the operator is able to stop flow of steel momentarily to allow some solidification to take place, and subsequently resume teeming until the metal reaches the proper level within the hot top. Without the indication which my invention furnishes, the operator has no certain way of knowing exactly when to stop the flow of steel and hence must act largely by guess.

While I have shown and described only a single embodiment of my invention, it is apparent that modifications may arise. Therefore, I do not wish to be limited to the disclosure set forth but only by the scope of the appended claims.

I claim:

1. The combination, with a mold adapted to receive molten metal, of a device for indicating the rise of metal therein to a predetermined level comprising a strip of magnesium and means supporting said strip at said level but out of the direct path of metal poured into the mold, said strip being ignited by heat of the molten metal on reaching this level and thus producing a conspicuous flare.

2. The combination, with an ingot mold and a hot top mounted at the top thereof with its lower end projecting into the mold cavity, of a device for indicating the rise of molten metal in the mold to the bottom of the hot top comprising a strip of magnesium and means supporting said strip within the mold but outside the hot top out of the direct path of metal teemed into the mold and adjacent the lower end of the hot top, said strip being ignited by heat of the molten metal on reaching the lower end of the hot top and thus producing a conspicuous flare.

3. The combination, with an ingot mold having a cavity adapted to receive molten metal and an opening at the top through which molten metal can be poured into said cavity, and a hot top mounted at the top of said mold and extending through said opening part way into said cavity, of a device for indicating the rise of molten metal in said cavity to the bottom of said hot top comprising a mass of material which is easily ignited and burns with a conspicuous flare, and means supporting said mass within said cavity at the bottom of said hot top, said mass being located outside said hot top and protected by said hot top from direct contact with metal poured through said opening, whereby said mass ignites only when metal rises in said cavity to the bottom of said hot top.
